CLAIM

I claim the ornamental design for a hand held 3D scanning device, as shown and described.

DESCRIPTION

FIG. 1 is a perspective view of a hand held 3D scanning device showing my new design;
FIG. 2 is a top plan view thereof;
FIG. 3 is a bottom view thereof;
FIG. 4 is a front elevation view thereof;
FIG. 5 is a rear elevation view thereof;
FIG. 6 is a side elevation view thereof; and,
FIG. 7 is an opposite side elevation view thereof.
